UNITED STATES PATENT OFFICE

146,135

DESIGN FOR A DOILY OR SIMILAR ARTICLE

Kenneth C. Hamilton, Milwaukee, Wis., assignor to Milwaukee Lace Paper Company, Milwaukee,
Wis., a corporation of Wisconsin
Application July 22, 1946, Serial No. 131,822

Term of patent 14 years

(Cl. D3—9)

To all whom it may concern:

Be it known that I, Kenneth C. Hamilton, a citizen of the United States, residing at Milwaukee, in the county of Milwaukee and State of Wisconsin, have invented a new, original, and ornamental Design for a Doily or Similar Article, of which the following is a specification, reference being had to the accompanying drawing, forming a part thereof.

The single figure of the drawing is a face view of a doily embodying my new design. While my design is shown as delineated on a doily, it is contemplated that the same may be applied to other similar articles without departing from the spirit of the invention.

I claim:

The ornamental design for a doily or similar article, substantially as shown and described.

KENNETH C. HAMILTON.
